UNITED STATES PATENT OFFICE.

HARRY G. WEBSTER, OF CHICAGO, ILLINOIS, ASSIGNOR TO MILO G. KELLOGG, OF CHICAGO,
ILLINOIS.

SIGNALING SYSTEM.

No. 921,320.

Specification of Letters Patent. Patented May 11, 1909.

Application filed July 5, 1906. Serial No. 321,320.

To all whom it may concern:

Be it known that I, HARRY G. WEBSTER, a citizen of the United States, and resident of the city of Chicago, county of Cook, and State of Illinois, have invented certain new and useful Improvements in Signaling Systems, of which the following is a specification.

This invention relates to signaling systems in which the signals originating at any of a plurality of individual circuits are received upon a common register or other signal-receiving device. Its object is to provide improved means whereby the accidental grounding or short circuiting of any individual circuit will operate to isolate such circuit from the receiving device and thus prevent interference with signals originating on other individual circuits.

In accordance with my invention, I associate with each individual circuit a so-called "double acting" relay. Relays of this type are characterized by the fact that their contacts have two operative positions other than normal, and in my invention the contacts of this relay assume one operative position in response to a lesser or normal energization of the relay magnet, and the other operative position in response to a greater or abnormal energization of the relay magnet. In its normal operation, the circuit of the relay is completed through a relatively high resistance, causing the normal energization of the relay, and the consequent actuation of its contacts serves to control and operate a register or other signal-receiving device. If, however, the wires of the individual circuit become accidentally grounded or short circuited, an increased current will flow through the relay, causing the abnormal energization of its magnet, and the consequent actuation of its contacts operates to dissociate the common receiving device from the circuit in trouble and also to cause the display of a signal individual to the circuit. Upon the removal of the accidental short circuit or ground, the relay contacts assume their normal position.

The invention will be more fully understood from the accompanying drawing, in which—

Figure 1 illustrates my invention as applied to a combined telephone exchange and alarm system in which the individual telephone circuits also constitute individual cir-

cuits separate from their telephonic use. In this figure, the common register or receiving device is included in a normally open circuit. In Fig. 2 I have illustrated one form of double-acting relay having contacts arranged in accordance with the diagram of Fig. 1. Fig. 3 is a diagram indicating the general structure of Fig. 1, but differing therefrom in that the receiving device is included in a normally closed circuit.

Referring to Fig. 1, the telephone system thus indicated is that illustrated and described in United States Patent No. 647,588, dated April 17, 1900. In this system, current is furnished to the two limbs of the line from a central battery C, normally through the line relay 12 and the return side of the battery. Upon the insertion of a connecting plug, current is furnished to the line through the two windings of a repeating coil associated with the cord circuit and the cut-off relay 11 is operated to disconnect the normal line relay and return connections. The substation apparatus is indicated as 80 having a call-bell b and condenser c normally in bridge of the limbs 1 and 2 of the line; and upon the elevation of the switchhook h, this bridge is interrupted and an alternate one closed, including the receiver 85 r and transmitter t. When a circuit is closed through this last mentioned bridge, as when the subscriber initiates a call, current will flow from battery C, through line relay 12, limb 1, receiver r and transmitter t and limb 90 2 to the return side of the central battery. The operator answers in the usual way and the insertion of the connecting plug maintains a flow of current in the line limbs and energizes the cut-off relay 11 to disconnect 95 the normal battery connections of the line limbs, all as set forth in the above mentioned patent.

To provide for the separate signaling function of the system, a double-acting relay B, having differential windings 4—5, is included in circuit with the two line limbs; and a signal-transmitting device of any preferred type is connected from that line limb associated with the active terminal of the 105 battery, through a relatively high resistance a, to ground. This is indicated at F as the ordinary call-box provided with a make-and-break wheel w engaging spring s upon its revolution in response to the depression 110

and release of the handle of lever d , and a manually operated circuit-closing key is also shown at k . On account of the differential connection of the windings of relay B , the relay is not energized by current flowing through both line limbs in the regular telephonic operation of the system, but when a special signal is to be transmitted, the operation of key k or wheel w intermittently 10 closes a circuit which may be traced from the central source of current, through the winding 5 of relay B , limb 1 of the line, the circuit-closing device and resistance a to ground. This current will be of relatively small value and will energize relay B to an extent sufficient only to cause armature 6 to engage contact 8 without moving contact 7 out of engagement with contact 7, and thus operates the register R in the well-known manner.

In the diagram of Fig. 1, A represents a complete line extending to a substation and to the signal-transmitting device, while at A' and A^2 are indicated similar lines 25 equipped with relays B' and B^2 , corresponding to relay B . If, through any cause, limb 1 of either of the lines becomes accidentally grounded, it is evident that the resistance a being then excluded, a current will flow 30 through winding 5 of relay B , B' or B^2 of considerably greater value than that due to the operation of the signaling device F . The greater energization of the relay, due to this increased flow of current, is sufficient 35 to completely actuate armature 6. By this actuation, contact 8 is moved out of engagement with contact 7, thus dissociating the register R from the relay; and the subsequent engagement of contact 8 with contact 40 9 completes a circuit for lamp 10, which may be traced from the upper terminal of battery C , through wire 20, lamp 10, contacts 9, 8 and 6, and wire 21 to the return side of the battery. The ensuing current in this 45 circuit causes the illumination of lamp 10, thus indicating to the attendant that the line is in trouble and at the same time preventing interference with the other lines of the system. When the trouble is removed, the 50 interruption of the current flowing through winding 5 allows the relay contacts to assume their normal positions in readiness for the normal signal.

Fig. 2 illustrates one form of double-acting relay which may advantageously be used in the structure of Fig. 1. It consists of an electromagnet whose core 14 has an angular extension 15 of magnetic material which serves as a support for the armature 16 and for the circuit-changing springs 6, 7, 8 and 9, and also to extend the magnetic circuit to the armature. These springs are numbered to correspond with the contacts 60 diagrammatically illustrated in Fig. 1. The armature is provided with a stop 17, and

spring 8 is provided with an adjustable tension-screw 18. When the relay winding is traversed by a relatively weak current, the ensuing partial energization of the core causes the lower end of the armature 16 to be attracted sufficiently to cause spring 6 to engage spring 8, but, the latter spring being of relatively heavy material and provided with the tension-screw 18, it serves as a stop to the further motion of the armature. When, however, the relay winding is traversed by a relatively great current, the armature is completely attracted, causing the stop 17 to engage the end of the core 14, and the spring 8 being engaged by the 75 spring 6 to move out of engagement with spring 7 and engage spring 9, thus giving the two operative positions of the contacts required in the structure of Fig. 1.

Fig. 3 shows diagrammatically the three 85 lines A , A' , A^2 and their respective relays B , B' , B^2 of Fig. 1, but the register R' is included in a normally closed circuit of battery E , which may be traced through armature 6 and contact 19 of relay B to 90 armature 6 and contact 19 of relay B' , and armature 6 and contact 19 of relay B^2 . When any of the relays are energized by the weaker pulsations set up in sending a signal, armature 6 makes and breaks circuit with 95 contact 19, thus operating the register R' , but is not sufficiently attracted to move contact 8. If, however, one of the lines become grounded, the complete attraction of armature 6 engages contact 8 and moves it 100 into engagement with contact 9, thus completing a new circuit for register R' which includes the particular signal lamp 10 which is associated with the line in trouble. This action causes the illumination 105 of the signal lamp to give the necessary indication and likewise maintains a circuit for register R' which allows its operation by signals originating on other circuits.

It will be evident that any form of electrical signal may be substituted for the lamp 10 and that current for the operation of the double-acting relays may be furnished in a variety of ways. It is also evident that the double-acting relay may be constructed 115 otherwise than as indicated in Fig. 2. It is also obvious that my invention is not limited to a combined telephone and alarm system, but may be embodied in various structures in which signals, arising on a plurality of 120 circuits, are received upon a common device, and that many alterations and modifications of the invention may be made without departing from its spirit. I therefore do not wish to be limited to the precise structures 125 indicated, but claim:

1. A signaling system comprising a plurality of individual circuits, a local transmitting apparatus connected to each circuit, a relay in each circuit, a signal receiving cir- 130

5. A circuit which is normally controlled by any of the relays, a source of electricity, switching mechanism individual to each relay operated whenever the relay is energized by current more than normal in magnitude to cut off the control of the receiving circuit by the relay, and signal receiving apparatus in the receiving circuit. 50
2. A signaling system comprising a plurality of individual circuits, a local transmitting apparatus connected to each circuit, a relay in each circuit, a signal receiving circuit which is normally controlled by any of the relays, a source of electricity, switching mechanism individual to each relay operated whenever the relay is energized by current more than normal in magnitude to cut off the control of the receiving circuit by the relay, a signal associated with the relay adapted to be displayed when the control is so cut off, and signal receiving apparatus in the receiving circuit. 60
3. A signaling system comprising a plurality of individual circuits, a local transmitting apparatus connected to each circuit, a double-acting relay in each circuit, a signal receiving circuit which is normally controlled by any of the relays, a source of electricity, switching mechanism individual to each relay operated whenever the relay is energized by current more than normal in magnitude to cut off the control of the receiving circuit by the relay, a signal associated with the relay adapted to be displayed when the control is so cut off, and signal receiving apparatus in the receiving circuit. 65
4. A signaling system comprising a plurality of transmitting circuits, a source of electricity, a resistance, a relay in each circuit, a local transmitting apparatus connected to each circuit operating to include said relay in circuit with said source and said resistance, a signal receiving circuit which is controlled by any of the relays when so included, signal receiving apparatus included in the signal receiving circuit, switching mechanism associated with the relay operated when said relay is included in a low resistance circuit with said source exclusive of said resistance to cut off the control of the receiving circuit by the relay and to restore said control when said low resistance circuit is interrupted. 70
5. A signaling system comprising a plurality of transmitting circuits, a source of electricity, a resistance, a relay in each circuit, a local transmitting apparatus connected to each circuit operating to include said relay in circuit with said source and said resistance, a signal receiving circuit which is controlled by any of the relays when so included, signal receiving apparatus included in the signal receiving circuit, switching mechanism associated with the relay operated when said relay is included in a low resistance circuit with said source exclusive of said resistance to cut off the control of the receiving circuit by the relay and to restore said control when said low resistance circuit is interrupted. 75
6. A signaling system comprising a plurality of transmitting circuits, a source of electricity, a resistance, a relay in each circuit, a local transmitting apparatus connected to each circuit operating to include said relay in circuit with said source and said resistance, a signal receiving circuit which is controlled by any of the relays when so included, signal receiving apparatus included in the signal receiving circuit, switching mechanism associated with the relay operated when said relay is included in a low resistance circuit with said source exclusive of said resistance to cut off the control of the receiving circuit by the relay and to restore said control when said low resistance circuit is interrupted, and an indicator associated with the individual circuit adapted to be displayed when the control is cut off. 80

Correction in Letters Patent No. 921,320.

It is hereby certified that in Letters Patent No. 921,320, granted May 11, 1909, upon the application of Harry G. Webster, of Chicago, Illinois, for an improvement in "Signaling Systems," an error appears in the printed specification requiring correction, as follows: In line 55, page 1, after the word "individual," the word *signaling* should be inserted; and that the said Letters Patent should be read with this correction therein that the same may conform to the record of the case in the Patent Office.

Signed and sealed this 13th day of June, A. D., 1909.

C. C. BILLINGS,
Acting Commissioner of Patents.

cuit which is normally controlled by any of the relays, a source of electricity, switching mechanism individual to each relay operated whenever the relay is energized by current more than normal in magnitude to cut off the control of the receiving circuit by the relay, and signal receiving apparatus in the receiving circuit.

2. A signaling system comprising a plurality of individual circuits, a local transmitting apparatus connected to each circuit, a relay in each circuit, a signal receiving circuit which is normally controlled by any of the relays, a source of electricity, switching mechanism individual to each relay operated whenever the relay is energized by current more than normal in magnitude to cut off the control of the receiving circuit by the relay, a signal associated with the relay adapted to be displayed when the control is so cut off, and signal receiving apparatus in the receiving circuit.

3. A signaling system comprising a plurality of individual circuits, a local transmitting apparatus connected to each circuit, a double-acting relay in each circuit, a signal receiving circuit which is normally controlled by any of the relays, a source of electricity, switching mechanism individual to each relay operated whenever the relay is energized by current more than normal in magnitude to cut off the control of the receiving circuit by the relay, a signal associated with the relay adapted to be displayed when the control is so cut off, and signal receiving apparatus in the receiving circuit.

4. A signaling system comprising a plurality of transmitting circuits, a source of electricity, a resistance, a relay in each circuit, a local transmitting apparatus connected to each circuit operating to include said relay in circuit with said source and said resistance, a signal receiving circuit which is controlled by any of the relays when so included, signal receiving apparatus included in the signal receiving circuit, switching mechanism associated with the relay operated when said relay is included in a low resistance circuit with said source exclusive of said resistance to cut off the control of the receiving circuit by the relay and to restore said control when said low resistance circuit is interrupted, and an indicator associated with the individual circuit adapted to be displayed when the control is cut off.

with the relay operated when said relay is included in a low resistance circuit with said source exclusive of said resistance to cut off the control of the receiving circuit by the relay.

5. A signaling system comprising a plurality of transmitting circuits, a source of electricity, a resistance, a relay in each circuit, a local transmitting apparatus connected to each circuit operating to include said relay in circuit with said source and said resistance, a signal receiving circuit which is controlled by any of the relays when so included, signal receiving apparatus included in the signal receiving circuit, and switching mechanism associated with the relay operated when said relay is included in a low resistance circuit with said source exclusive of said resistance to cut off the control of the receiving circuit by the relay and to restore said control when said low resistance circuit is interrupted.

6. A signaling system comprising a plurality of transmitting circuits, a source of electricity, a resistance, a relay in each circuit, a local transmitting apparatus connected to each circuit operating to include said relay in circuit with said source and said resistance, a signal receiving circuit which is controlled by any of the relays when so included, signal receiving apparatus included in the signal receiving circuit, switching mechanism associated with the relay operated when said relay is included in a low resistance circuit with said source exclusive of said resistance to cut off the control of the receiving circuit by the relay and to restore said control when said low resistance circuit is interrupted, and an indicator associated with the individual circuit adapted to be displayed when the control is cut off.

In witness whereof, I hereunto subscribe my name this 30th day of June 1906.
